(57) **CLAIM**

The ornamental design for a portion of a toner cartridge, as shown and described.

DESCRIPTION

FIG. 1 is a front, top and left side perspective view of a portion of a toner cartridge, showing my new design;

FIG. 2 is a rear, top and right side perspective view thereof;

FIG. 3 is a front, top and right side perspective view thereof;

FIG. 4 is a rear, top and left side perspective view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a right side elevational view thereof, shown at an enlarged scale;

FIG. 10 is a left side elevational view thereof;

FIG. 11 is a cross-section view taken along line 11—11 in FIG. 5; and,

FIG. 12 is a cross-section view taken along line 12—12 and between lines 12a—12a and 12b—12b in FIG. 7.

The broken lines are for illustrative purposes only and form no part of the claimed design.
